R. P. HAYDEN

SYSTEM OF ROLLING SURGICAL ADHESIVE PLASTER

Filed Sept. 3, 1926

Inventor

R. P. HAYDEN,

By *Jas. Richardson* Attorney

UNITED STATES PATENT OFFICE.

ROBERT P. HAYDEN, OF NEW BRUNSWICK, NEW JERSEY, ASSIGNOR TO JOHNSON & JOHNSON, OF NEW BRUNSWICK, NEW JERSEY, A CORPORATION OF NEW JERSEY.

SYSTEM OF ROLLING SURGICAL ADHESIVE PLASTER.

Application filed September 3, 1926. Serial No. 133,397.

Adhesive plaster for hospital use is usually put up in five yard lengths, twelve inches wide, in roll form with an intervening face cloth to prevent promiscuous sticking and to facilitate the unwinding of the plaster in service. It has been proposed to divide the face cloth longitudinally to simplify the separation of the plaster and this is sometimes practiced. But this practice suffers the disadvantage that the face cloth, during the winding operation, has a tendency to pucker or buckle transversely, which obviously retards even winding.

The object of my invention is to provide for covering adhesive plaster in such way as to obviate the objections and disadvantages of the old practice and in such way as to provide for the ready separation of the plaster.

The nature, characteristic features and scope of the invention more readily will be understood from the following description taken in connection with the accompanying drawing forming a part hereof, wherein

Figure 1 is a perspective view of a roll of plaster embodying my improvements.

Fig. 2 is a sectional view.

According to my invention, adhesive plaster 5 is rolled with an intervening cover or facing strip, consisting of longitudinal sections 6 having their proximate edges 7 in overlapping relation and one or both turned or longitudinally folded as at 8. In further accordance with my inventive thought, the outer or remote edges of the facing sections are turned or inwardly folded as at 9. The effect of this is to establish distance or spacing elements substantially the same as the medial spacing elements or lapped edges 40 of the facing section; and the net result is uniform rolling of the plaster and facing sections, the latter being maintained in parallelism. Under the provision stated, puck-

ering, buckling or wrinkling of the facing strip and of the plaster is eliminated in a 45 positive manner.

Aside from their office of providing for uniform winding of the facing sections in parallelism, the turned edges afford purchase points to facilitate the ready separation of the facing sections of the plaster.

Having described my invention, I claim:

1. The method of preventing puckering of facing cloths in rolled adhesive plaster, which consists in turning the margins 55 thereof.

2. The method of preventing puckering of facing cloths in rolled adhesive plaster, which consists in inwardly turning the margins. 60

3. The method of preventing puckering of facing cloths in rolled adhesive plaster, which consists in providing separate strips having proximate edges in overlapping relation and having remote edges turned to substantially coincide with the thickness of the overlap. 65

4. The method of preventing puckering of facing cloths in rolled adhesive plaster, which consists in providing cloth sections 70 whereof the proximate edges are in overlapping relation and at least one of them turned, and turning the outer margins of the cloth sections so that they will substantially coincide in thickness with the overlapped 75 margins.

5. A roll of adhesive plaster having a facing cloth, consisting of crinoline sections having their proximate edges in overlapping relation throughout the roll, and having 80 their remote edges inwardly folded to substantially coincide with the thickness of the lapped edges.

In testimony whereof I affix my signature.

ROBERT P. HAYDEN.
